HOLDER FOR A DRINKING GLASS OR THE LIKE

Malcolm C. Jones, 954 Junipero Drive, Costa Mesa, Calif.

Filed Dec. 9, 1963, Ser. No. 77,713

Term of patent 14 years

(Cl. D4—3)

FIG. 1.

FIG. 2.

FIG. 3.

FIG. 4.

FIG. 1 is a perspective view of a holder for a drinking glass or the like showing my new design;

FIG. 2 is a side elevation thereof;

FIG. 3 is a top view thereof; and,

FIG. 4 is a bottom view thereof.

I claim:

The ornamental design for a holder for a drinking glass or the like, as shown.
